UNITED STATES PATENT OFFICE.

JOHN M. WHEATON, OF SOUTH ROYALSTON, MASSACHUSETTS, ASSIGNOR TO CROMPTON & KNOWLES LOOM WORKS, OF WORCESTER, MASSACHUSETTS, A CORPORATION OF MASSACHUSETTS.

SHUTTLE-CHECK.

1,265,015.

Specification of Letters Patent.

Patented May 7, 1918.

Application filed July 23, 1917. Serial No. 182,150.

To all whom it may concern:

Be it known that I, JOHN M. WHEATON, a citizen of the United States, residing at South Royalston, in the county of Worcester 5 and State of Massachusetts, have invented a new and useful Shuttle-Check, of which the following is a specification.

This invention relates to a shuttle check of the type in which increased pressure is applied to the shuttle through the shuttle 10 binder as the shuttle approaches its final boxed position.

Such checks as heretofore designed have continuously increased the binder pressure 15 until the shuttle is brought to rest, thus requiring that the shuttle shall be picked from the box against the maximum binder resistance, a construction which has obvious disadvantages.

It is the object of my present invention to improve the construction of shuttle checks of this type by providing devices which maintain a uniform increased pressure of the binder on the shuttle during the final 20 boxing of the shuttle, after the speed of the shuttle has been materially reduced.

With this general object in view an important feature of my invention in the preferred form relates to the provision of a 25 shuttle actuated member having a cam portion operative to apply increasing pressure to the shuttle through the binder, and having also a straight or uniform portion adapted to maintain a constant binder pressure 30 during the final movement of the shuttle to boxed position.

Further features of my invention relate to the provision of yielding connections between said shuttle actuated member and the 35 shuttle binder, and also to means for adjusting the final binder pressure.

My invention further relates to arrangements and combinations of parts hereinafter described and more particularly pointed out 40 in the appended claims.

A preferred form of my invention is shown in the drawings, in which—

Figure 1 is a top plan view of a shuttle 45 box having my improved shuttle check mounted thereon;

Fig. 2 is a front elevation of the parts shown in Fig. 1, and

Fig. 3 is a transverse sectional elevation taken along the line 3—3 in Fig. 1.

Referring to the drawings, I have shown 55 my improved shuttle check applied to a loom in which the shuttle S is engaged by a picker 10 slidable upon a rod 11 and actuated by a picker stick 12, all of the usual construction. The type of picker is, however, immaterial. The rod 11 is rigidly supported upon the lay 13 to which is also secured the plate 14 forming the rear side of the shuttle box.

The front face of the shuttle is engaged by a binder 15 riveted or otherwise secured to a member 16 pivoted at 17 to a projection on the lay 13. An arm 18 is also mounted to swing about the pivot 17 and is yieldingly connected to the extension 19 of the 70 member 16 by a bolt 20 and a compression spring 21. At its outer end the arm 18 is provided with a roll 22 positioned for engagement by the cam-shaped head of a shuttle-actuated member 23 pivoted at 24 (Fig. 75 2) to a bracket 25 supported by the lay 13. The upper rear portion of the member 23 may be provided with a covering 26 of leather or other wear-resisting material, this portion of the member 23 being engaged on 80 one side by the picker 10 and on the opposite side by a bunter or stop 27 fixed in the end of the lay.

The cam-shaped head of the member 23 comprises an inclined portion 28 and a 85 straight portion 29. A spring 30 (Fig. 3) is connected at one end to the bracket 25 and at its opposite end to a collar 31 on the pivot shaft 24 of the member 23, the spring normally moving the member 23 away from the 90 end of the shuttle box until it engages an adjustable stop screw 32 (Fig. 2). The usual binder spring 33 is provided for applying normal pressure to the binder 15.

As the shuttle S enters the shuttle box it 95 first encounters this normal pressure of the binder 15 by which its speed is reduced until it forces the picker 10 against the leather facing of the member 23. The member 23 is then moved toward the end of the shuttle 100 box and the cam surface 28 of said member forces the cam roll 22 and arm 18 outwardly, thus compressing the spring 21 and increasing the pressure of the binder 15. The pressure continues to increase until the straight 105 portion 29 of the member 23 engages the roll 22, after which engagement the pressure is maintained constant until the shuttle

reaches its final boxed position. The final pressure may be adjusted by use of the bolt 20.

It will thus appear that the binder pressure is increased during the first part of the engagement of the member 23 with the roll 22, but that as the speed of the shuttle decreases further increase of pressure is avoided, the binder maintaining a practically uniform pressure upon the shuttle during its final movement to boxed position. Furthermore, the spring 21 acting through the cam roll 22 and cam surface 28 causes the pivoted member 23 to directly resist the movement of the picker 10 and shuttle S. Such resistance diminishes abruptly when the cam roll engages the straight surface 29 on the member 23.

This method of applying pressure to the shuttle is found to possess important advantages in operation, particularly by reducing the maximum or final binder pressure, and thus reducing the power required to pick the shuttle.

Having thus described my invention, it will be evident that changes and modifications can be made therein by those skilled in the art without departing from the spirit and scope of my invention as set forth in the claims, and I do not wish to be otherwise limited to the details herein disclosed, but what I claim is:—

1. In a loom, in combination, a shuttle, a shuttle box, a binder, a picker, a member movable with said picker, and a yielding connection between said member and said binder, said connection including means through which movement of said member with said picker is effective to first apply increasing pressure to said shuttle through said binder and to thereafter apply uniform pressure during the final boxing of the shuttle.

2. In a loom, in combination, a shuttle, a shuttle box, a binder a picker, a member movable with said picker, and a connection between said member and said binder including a spring, a cam, and a cam follower, said member through said connections being effective to first apply increasing pressure to said shuttle through said binder and to thereafter apply uniform pressure thereto.

3. In a loom, in combination, a shuttle, a

shuttle box, a binder, a picker, a member movable with said picker, and yielding connections between said member and said binder, said connections causing said member to directly resist movement of said picker and shuttle, and simultaneously applying increasing pressure on said shuttle through said binder, said direct resistance being thereafter diminished and said binder pressure being maintained uniform as the shuttle approaches final boxed position.

4. In a loom, in combination, a shuttle, a shuttle box, a binder, a picker, a member movable with said picker, and a connection from said member to said binder, said member having a cam element acting through said connection by which said member is effective to first apply increasing pressure to said shuttle through said binder and to thereafter apply uniform pressure thereto during the final boxing of the shuttle.

5. In a loom, in combination, a shuttle, a shuttle box, a member movable by said shuttle as it approaches final position in the shuttle box, a cam portion on said member and a straight portion adjacent said cam portion, a binder, and a cam roll yieldingly connected to said binder and positioned for successive engagement by said cam portion and said straight portion of said member.

6. In a loom, a shuttle, a binder, a shuttle-actuated member having a cam portion and a straight portion thereon, and a spring-connected arm through which said cam portion applies increasing pressure to the binder, and through which said straight portion maintains uniform pressure thereon during the final movement of the shuttle to boxed position.

7. In a loom, a shuttle, a lay, a binder pivoted to the lay, an arm mounted to swing about the same pivot, an adjustable spring connection between said arm and binder, a cam roll on said arm, and a shuttle-actuated member having a cam portion and a straight portion both positioned to engage said roll and to thereby apply increasing pressure to the binder and to thereafter maintain said increased pressure during the final boxing of the shuttle.

In testimony whereof I have hereunto affixed my signature.

JOHN M. WHEATON.
